UNITED STATES PATENT OFFICE.

AXEL L. SANDELS, OF CHICAGO, ILLINOIS.

MECHANICAL MOVEMENT.

1,293,556.

Specification of Letters Patent.

Patented Feb. 4, 1919.

Application filed March 9, 1917. Serial No. 153,655.

To all whom it may concern:

Be it known that I, AXELL SANDELS, subject of the King of Sweden, residing at Chicago, in the county of Cook and State of Illinois, have invented certain new and useful Improvements in Mechanical Movements; and I do hereby declare the following to be a full, clear, and exact description of the invention, such as will enable others skilled in the art to which it appertains to make and use the same.

This invention relates to improvements in mechanism for vibrating screens, particularly of the type for screening coal and the like, but which is adaptable for screens for all purposes.

The object of the invention is to provide a novel mechanism for imparting to a set of screens a reciprocatory motion variable in speed whereby to effect conveyance of the material longitudinally of the screen over portions of gradually increasing mesh without the aid of additional conveying means.

A further object of the invention is to provide mechanism for reciprocating a screen and conveyer, or a multiplicity of screens at a variable speed, in which the screens move simultaneously in opposite directions at variable speed whereby to balance or partially balance the strains and stresses on the actuating mechanism.

A further object of the invention is to provide mechanism for vibrating or reciprocating screens and the like, at variable speed, in which the strokes of the screen at high and low speeds respectively, may be adjusted and varied as desired to provide maximum efficiency of operation.

The invention consists in the features of construction and combinations of parts hereinafter fully described and particularly claimed.

In the accompanying drawings illustrating a suitable embodiment of my invention, Figure —1— is a view in side elevation of a coal-screening apparatus constructed in accordance with the invention.

Fig. —2— is a fragmentary top plan view of the same.

Fig. —3— is a view in plan section partly in elevation showing the mechanism for operating the various screen members, said view being substantially diagrammatic.

Fig. —4— is a similar fragmentary section through the completed motion-transmitting mechanism.

Fig. —5— is a vertical longitudinal section of the same on the line 5—5 of Fig. —1—.

Fig. —6— is a detail vertical longitudinal section showing the relative positions of the three eccentrics driven at variable speeds for simultaneously imparting variable speed to three elements.

Figs. —7— and —8— are fragmentary detail diagrammatic views illustrating the difference in direction of feed occasioned by changing the position of the actuating eccentrics relatively to the cranks rigid therewith and connected to the source of power or drive-shaft actuating said eccentrics.

Fig. —9— is a diagrammatic view showing the various positions of the link connecting the disks during one revolution of the same.

In carrying out my invention, I make use of a well-known mechanism or mechanical movement for transforming uniform rotary movement of one element into variable movement of another member geared thereto by means of a crank on the actuating member connected with the actuated member by means of a link or pitman which, generally, is very short and, during rotation of the crank, becomes positioned at various angles relative to the driven member of the plane of movement thereof, whereby the latter is moved at a speed varied in accordance with the variations or differences in angles of disposition of the link or pitman.

In the present invention the uniform motion of the drive-shaft is first transmitted, as hereinafter fully described, to counter-shafts, and from the latter to the reciprocating elements for varying the speed of reciprocation of the latter and simultaneously effecting movement thereof in respectively opposite directions.

Referring now to the drawings, 1 indicates a drive-shaft suitably geared to a source of power as, for example, by means of the pulley 2. The said drive-shaft is provided at one end with two diametrically opposed equal crank arms 3 each equipped with a crank pin.

Disposed axially parallel with and eccentric to the drive-shaft 1 is a solid counter-shaft 4, and a hollow counter-shaft 5, the latter being mounted on the shaft 4, and being rotatable relatively to the latter on the same axis. The shaft 4 is provided with a crank arm 6, and the shaft 5 with a crank arm 7,

each of the latter being equipped with a crank pin having its axis disposed equi-distantly from the axis of the shaft 4 and preferably also spaced radially as far from the 5 axis of the shaft 4 as the crank pins of the crank arms 3 are spaced from the axis of the shaft 1. The spacing of the axes of the shafts 1 and 4 with respect to each other is less than the radial distance of any one of 10 the crank pins from the axis of rotation of the shaft with which it is rigid. A link 8 connects one of the crank pins of the arm 3 with the crank pin of the arm 6 of the shaft 4 and a similar link 9 connects the other 15 crank pin of the arm 3 with the crank pin of the arm 7 of the shaft 5. The length of the links 8 and 9 with respect to the distance between the centers of the openings therein engaging the respective crank pins is also 20 greater than the distance separating the axes of rotation of the shafts 1 and 4, and is preferably equal to the radial distance of each crank pin from the axis of rotation of the shaft with which it is rigid.

25 The result of this arrangement is, as diagrammatically illustrated in Fig. —9—, that during the half revolution of the shaft 1 from point *a* to point *g* the shaft 4 will be rotated through the arc greater than one 30 hundred and eighty degrees from point *a'* to point *g'*. The extent of the last-named arc in proportion to the first-named is dependent upon the distance between centers of shafts 1 and 4. From this it will be observed 35 that the counter-shafts 4 and 5 will rotate at a variable speed, and that each thereof will attain its greatest speed of rotation substantially at the time that the other thereof has attained its least speed. This is due to 40 the fact that the crank pins of the arm 3 of the shaft 1 are diametrically oppositely disposed and on the assumption that the eccentrics 10 and 11 of the shafts 4 and 5 are disposed so that the longest radius of each from 45 the axis of rotation is coincident with the radius intersecting the crank pin axis of said shafts 4 and 5. The eccentric 10 of the shaft 4 is connected by means of an eccentric rod 12 and eccentric strap 13 with the 50 upper or screen member 14 of the coal screen or the like, adapted to be actuated by the mechanism, and the eccentric 11 of the shaft 5 is similarly connected by means of the eccentric rod 15 and eccentric strap 16 with the other or conveyer member 17, shown in Fig. —1—, it being obvious, of course, that either of said eccentrics may be interchangeably connected with said members 14 and 17. Another eccentric 18 on the shaft 4 (or 5, if desired) but positioned differently from the companion eccentric on said shaft, is connected by means of the eccentric rod 19 and eccentric strap 20 with the movable bottom plate of a feed-spout 21 of a hopper 22 55 containing the coal or other material to be

screened, and which is adapted to be fed longitudinally of the members 14 and 17 and fed into the cars or other receptacles 23 disposed below the member 17.

In practice, the member 14 is provided 70 with a foraminous bottom wall or foraminous portions, in said bottom wall, as indicated at 24 and 25 respectively, the perforations in the portion 24 being comparatively small so as to separate all of the very 75 fine particles from the mass of coal or other material fed upon the screens, and the perforations in the portion 25 being larger to separate medium-sized lumps from the mass; the balance or larger lumps passing 80 from the end of the member 14 upon the end portion of the member 17, and dropping from the latter into the farthest left-hand car or receptacle 23. The member 17 consists practically of a solid platform or 85 trough, which is provided with gated or valved openings 26 and 27 through which the material falling through the portion 24 of the member 14, and through the portion 25 of the same respectively, are adapted to 90 be delivered into the right-hand receptacles 23; the details of construction of this portion of the apparatus constituting no 95 part of the present invention.

The feed member 21 is reciprocated for 95 the purpose of feeding coal or other material to be screened upon the member 14 with sufficient rapidity to keep the latter sufficiently loaded to perform its functions properly.

100 The object of imparting variable speed reciprocatory motion to the several elements 14, 17 and 21 is to cause the coal or other material to be thrown always in one direction longitudinally of said members, and to this end it is desirable to move them to their forward limits of motion beginning relatively slowly and with constantly increasing rapidity so as to attain substantially maximum speed as the forward limit 110 of movement is reached, the return movement beginning very rapidly and gradually decelerating whereby the supporting surface for the coal is partially withdrawn from underneath the latter so that it does 115 not travel back with the said members, but retains an advanced position thereon, and is thus gradually moved from end to end thereof, at the same time being agitated sufficiently to effect the sifting or screening 120 desired.

125 The point at which the member 14, for example, attains its maximum speed is determinable by the relative positions of the axes of rotation of the shafts 1 and 4 with respect to their positions with regard to the planes of reciprocation of the members 14 and 17. As shown in Fig. —5—, the axis of the shafts 4 and 5 is disposed below and forward of the axis of the shaft 1 so that 130

a plane common to both axes would be disposed at an angle of substantially thirty-five degrees more or less, to the horizontal plane of reciprocation of the members 14 and 17. The variation of this angle will change the point in the travel of the members 14 and 17 respectively, at which said members attain their respective maximum speeds and minimum speeds. This may further be changed by varying the position of the eccentrics on said shafts with respect to the crank-radii thereof. Thus, as shown in Figs. —7— and —8— if the longest radius of the eccentric of one of said shafts is disposed to extend coincidentally and in the same direction as the crank pin radius thereof, the coal or other matter disposed on the member 14 or 17 geared to said eccentric will be fed in the direction of the arrow in Fig. —7—, whereas, if said eccentric is turned through an arc of one hundred and eighty degrees, as shown in Fig. —8—, the coal or other matter will be fed in the direction of the arrow in Fig. —8—. By turning the eccentric of either one of said shafts on the axis thereof relatively to the crank-pin radius thereof it will be obvious that the point in the stroke of the reciprocating member connected with said eccentric at which said reciprocating member attains its maximum speed will be similarly varied. The relative positions of crank pins and eccentrics illustrated in Figs. —1— to —6— inclusive, and the relative positions of the axes of the shafts 1 and 4 therein shown are not intended to illustrate what I have determined to be the best relative positions to produce the desired result in effecting not only the transportation and screening of the material deposited on the members 14 and 17, nor to produce the greatest degree of balancing effect on the shafts 1, 4 and 5 so as to minimize the strains on the latter for increasing the life of the mechanism, as it will be obvious that this may be readily determined by experiment. The balancing effect produced obviates the necessity of mounting the driving element on as heavy foundations as would be necessary were the action of the mechanism not balanced, or partially balanced.

It will be obvious, of course, that my invention is adapted to many uses besides that of screening, and may be changed and varied to particularly adapt it to any desired purpose without departing from the invention as defined in the appended claims.

I claim as my invention:

1. In an apparatus of the kind specified, a pair of screens adapted to be reciprocated, and means for effecting reciprocation thereof comprising a counter-shaft having two diametrically opposed eccentrics connected with said respective screens, a crank-pin on said counter-shaft, a drive-shaft having a

crank-pin radially equi-distant from its axis with the crank pin of said countershaft, and axially offset from said counter-shaft a distance less than the distance of said crank pins from the axes of their shafts, a link 70 of greater length than the distance between the axes of said shafts connecting said crank-pins, the crank-radius of one of said eccentrics on said counter-shaft being coincident with its crank-pin radius, a plane 75 common to both shaft axes being inclined to the direction of reciprocation of said screens, whereby the latter are simultaneously reciprocated at variable speeds in opposite directions. 80

2. In an apparatus of the kind specified, a pair of reciprocable screens, a drive-shaft having a crank-pin, a countershaft parallel with and offset from said drive-shaft a distance less than the crank-radius of the latter, a crank on the countershaft having a radius equal to that of the crank of the drive-shaft, a link of greater length than the distance separating the axes of said shafts connecting said crank pins, a plane 90 common to both shaft axes being inclined to the direction of reciprocation of said screens, and connection between said screens and said countershaft for reciprocating the latter simultaneously in opposite directions, 95 said connection including an eccentric on said countershaft having its longest radius coincident with its crank-pin radius.

3. In an apparatus of the kind specified, a drive-shaft having two cranks, two countershafts disposed axially parallel with and eccentric to said drive shaft and each having a crank, a link of greater length than the distance separating the axes of rotation of the shafts connecting each of the counter-shafts with a crank of the drive-shaft for imparting variable rotary speed to said respective counter-shafts, two relatively reciprocable members operatively engaged with said respective counter-shafts for causing each of the same to move more rapidly in one direction than the other, and to move simultaneously in opposite directions at respectively different speeds. 100

4. In an apparatus of the kind specified, 115 a drive-shaft having diametrically opposed crank-pins, two counter-shafts disposed one within the other and each having a crank-pin, the axis of said counter-shafts being eccentric to the axis of said drive-shaft, and links of greater length than the distance separating said axes connecting the respective crank-pins of said counter-shafts with the respective crank-pins of said drive-shaft, 120 an eccentric on each of said counter-shafts, 125 and a pair of reciprocable members operatively connected with said respective eccentrics.

5. In an apparatus of the kind specified, 130 a pair of relatively reciprocable members, a

drive-shaft having two crank-pins at one end, two countershafts disposed one within the other and each having a crank-pin at one end, said counter-shafts eccentric to said drive-shaft and connected with the latter by means of links connecting the crank-pins thereof with the crank-pins of said drive-shaft, said links of greater length than the distance separating the axes of said drive and counter-shafts, the latter disposed substantially in the plane of reciprocation of said members, and said drive-shaft disposed so that a plane common to the several axes of said shafts will be angularly disposed relatively to the plane of reciprocation of said members, an eccentric on each of the counter-shafts having its longest radius in the radial plane of the crank-pin of said shaft, and eccentric rods connecting said respective members with said respective counter-shafts.

6. In an apparatus of the kind specified, a pair of relatively reciprocable members, a drive-shaft having two diametrically opposed crank-pins at one end, two counter-shafts disposed one within the other and

each having a crank-pin at one end, said counter-shafts eccentric to said drive-shaft and connected with the latter by means of links connecting the crank-pins thereof with the crank-pins of said drive-shaft, said links being equal and of greater length than the distance separating the axes of said drive and counter-shafts, the latter disposed substantially in the plane of reciprocation of said members, and said drive-shaft disposed so that a plane common to the several axes of said shafts will be angularly disposed relatively to the plane of reciprocation of said members, an eccentric on each of the counter-shafts having its longest radius in the radial plane of the crank-pin of said shaft, and eccentric rods connecting said respective members with said respective counter-shafts.

In testimony whereof I have signed my name in presence of two subscribing witnesses.
